UNITED STATES PATENT OFFICE.

BARNET NEWLAND, OF NEW YORK, N. Y., ASSIGNOR TO INCANDESCENT SUPPLY COMPANY, A CORPORATION OF NEW YORK.

HOLDER FOR GLOBES.

1,417,939.

Specification of Letters Patent. Patented May 30, 1922.

Application filed July 26, 1921. Serial No. 487,691.

To all whom it may concern:

Be it known that I, BARNET NEWLAND, a citizen of the United States, and resident of New York city, in the county of New York and State of New York, have invented certain new and useful Improvements in Holders for Globes, of which the following is a specification.

My invention relates to holders for globes.

10 The manner of supporting globes is by means fastened thereto by screws that go through the globe itself. Globes commonly employed for this purpose are made of expensive glass and drilling screw holes in them is an operation that involves considerable waste through breakage of globes in the drilling operation and through cracking or breakage of globes due to the expansion of the screws inserted in the screw holes 20 therein, said expansion being caused by the heat generated by the illuminating means.

An added disadvantage is that if the screws become loosened or dislodged, the supporting means of the globe is gone with 25 the incident danger to the person who happens to be under the same, as well as expense of breakage. Further, the globe is not intentionally removable without considerable trouble in unscrewing at least three 30 screws to take it down.

By my invention I provide a holder for globes wherein the globe is readily removable and is held in position when in use without the use of screws, thereby obviating 35 the necessity of drilling holes in the globes.

By my invention I secure a screwless holder that, when in practical use, is so locked that it is impossible for the globe 40 to fall unless the holder is intentionally unlocked. Further, as no screws, solder, or other connecting means are employed, the holder can be easily unlocked, when desired, for cleaning or other purposes, by 45 merely pressing a button which causes the parts to be in position for disassembling.

In the accompanying drawings the figure 50 is a cross-section of the holder, showing the apron in the raised position in dotted lines.

Similar reference characters denote like parts in the several views.

There is a bell-shaped body 1, having at the top thereof vent holes 2 to permit the

escape of heat, said body having fastened at the top a heat diffusing shield 4, by means 55 of screw ring 3, the ring 3 being adapted to be attached to a chain or other supporting means. There is a vertical hole shown at 3' through ring 3, shield 4 and body 1, to permit the entry of electric wire inside the 60 body to be connected to the commercial socket and illuminating means.

The body 1 has a hole therein at 5 through which is inserted a button 6, held in projected position by a leaf spring 7 or similar 65 means. While I employ one such spring-pressed button, more than one can be used, and equivalent locking means may be used without departing from the spirit of my invention. 70

The screw-threaded flanges 17', are employed in the usual manner for supporting electric light socket or sockets. The apron 8 has leaves 9 hinged or pivoted thereto at 10, said leaves being flared at the loose ends 75 at 12, to form lips 13 for supporting the globe 14. While two such leaves are shown more than two can be used.

The body 1 is bell-shaped with the flare 80 at the bottom. Said flare serves the purpose of supporting the apron 8 as at 16 and at the same time keeps the leaves 9 in the extended position as at 17, thereby preventing the leaves from coming toward each other and releasing the globe. 85

In practice the parts are assembled as shown in the drawing. To take out the globe all that is necessary is to press the button 6, push up the apron 8 and the leaves 9 are released from the globe 14 and the globe is 90 easily removed. The drawing shows in dotted lines the apron in the raised position.

To insert the globe 14, the same steps are followed. Button 6 is pressed, apron 8 is pushed up, the loosely hanging leaves 9 are 95 placed under the rim of the globe 14 until the lips 13 of said leaves are in contact with the under surface of the rim of the globe at 15. The apron 8 is pushed down until the button 6 is again projected by spring pressure beyond the surface of the apron. 100

The globe cannot be released without raising the apron above the button 6 and the apron cannot be raised above the button 6 until the button has been pressed back substantially flush with the body 1. Thus the button 105

6 locks the parts in operative relation. Further, there is no tendency on the part of the apron to go upward beyond the button 6 because the weight of the apron and globe 5 holds the apron down in operative position, the locking means acting to prevent the globe from being released by an accidental upward push.

It will thus be seen that the aforementioned combination attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawings shall 20 be interpreted as illustrative and not in a limiting sense.

Having described my invention, what I regard as new and desire to secure by Letters Patent is—

25 1. A holder for globes comprising, in combination, a screw ring, heat shield, and bell-shaped body, a wire passage through said screw ring, heat shield and body, heat vents in and a spring pressed button projecting through said body, a removable apron, slidably mounted on said body, hinged leaves

fastened thereto, said leaves having flared lips at the ends thereof adapted to support the globe, the flare on said body being adapted to support said apron and keep the leaves 35 in contact with the globe, for the purpose described.

2. A holder for globes comprising, in combination, a screw ring, heat shield, and bell-shaped body, a wire passage through said 40 screw ring, heat shield and body, heat vents in and a spring pressed button projecting through said body, socket holding means, a removable apron, slidably mounted on said body, hinged leaves fastened thereto, said 45 leaves having flared lips at the ends thereof adapted to support the globe, the flare on said body being adapted to support said apron and keep the leaves in contact with the globe, for the purpose described. 50

3. A holder for globes comprising, in combination, a bell-shaped body and a removable apron having globe holding means, slidably mounted on said body, the flare on said body supporting the apron and keeping the leaves 55 in contact with the globe, and means to hold said body and apron in locked position, for the purposes described.

Signed at New York city, in the county of New York and State of New York, this 22nd day of July, 1921.

BARNET NEWLAND.
